UNITED STATES PATENT OFFICE

135,742

DESIGN FOR A LATHE CARRIAGE

William M. McConnell, McKeesport, Pa., assignor to Mackintosh-Hemphill Company, Pittsburgh,
Pa., a corporation of Delaware

Application August 21, 1942, Serial No. 107,987

Term of patent 14 years

To all whom it may concern:

Be it known that I, William M. McConnell, a citizen of the United States, residing in McKeesport, in the county of Allegheny and State of Pennsylvania, have invented a new, original, and ornamental Design for a Lathe Carriage, of which the following is a specification, reference being had to the accompanying drawing forming a part thereof.

The figure is a perspective view of the top, one side and one end of a lathe carriage, showing my new design.

The other side and end not shown are substantially plain.

I claim:

The ornamental design for a lathe carriage, substantially as shown and described.

WILLIAM M. McCONNELL.
